MOTOR VEHICLE RADIATOR

Filed May 22, 1935

FIG. 1

UNITED STATES PATENT OFFICE

2,079,222

MOTOR VEHICLE RADIATOR

Valentin Miller, Los Angeles Calif., assignor of
one-half to Otto C. Nagel, Los Angeles, Calif.

Application May 22, 1935, Serial No. 22,738

2 Claims. (Cl. 257—130)

My invention relates to a motor vehicle radiator and has for its principal object, the provision of a relatively simple, practical and inexpensive radiator of cellular structure that is constructed so as to provide a relatively high degree of heat radiating surface and the parts of the structure being formed and arranged so as to provide maximum strength and rigidity so that the radiator when in use will effectively resist strains and stresses that tend to bend or distort the radiator or to cause a separation of the joints thereof.

Further objects of my invention are, to generally improve upon and simplify the construction of the existing forms of motor vehicle radiators and to provide a cellular radiator that is capable of being readily fabricated, thus minimizing production costs.

With the foregoing and other objects in view my invention consists in certain novel features of construction and arrangements of parts that will be hereinafter more fully described and claimed and illustrated in the accompanying drawing in which:

Fig. 1 is a front elevational view of a portion of a radiator constructed in accordance with my invention.

Fig. 2 is an elevational view taken looking in the direction indicated by the arrow 2 in Fig. 1.

Fig. 3 is a horizontal section taken on the line 3—3 of Fig. 1.

Fig. 4 is a horizontal section taken on the line 4—4 of Fig. 1.

Fig. 5 is a perspective view of one of a series of identical plates that are utilized in the construction of the improved radiator.

Fig. 6 is a perspective view of a portion of one of the water ducts used in the construction of the radiator.

In the construction of my improved radiator, I employ a plurality of identical walls formed of thin sheet metal which when assembled produce a plurality of horizontally disposed air ducts and interposed between these air duct forming metal sheets, are vertically disposed water ducts, each formed from a pair of thin metal sheets.

The air duct forming sheets designated generally by A in Fig. 5 are bent into substantially zigzag shape to produce a plurality of inclined portions 10 of uniform width and length and between the upper and lower edges of these inclined portions 10, the metal is bent to form narrow walls 11 which when the parts of the radiator are properly assembled occupy vertical positions.

At short distances inset from the ends of the

vertical walls 11, the metal is slit vertically and the upper ends of said vertical slits are connected by a horizontally disposed slit that extends along the line of bend between the upper portion of the narrow vertical wall and the lower portion of the adjacent inclined wall 10 and the material between these slits is bent at right angles to the wall 11 so as to provide a horizontally disposed flange 12 that extends lengthwise of the air duct between the inclined portions 10 and functions as a cooling fin, inasmuch as the air which flows through the air ducts of the radiator passes directly over the surfaces of said fin or flange.

The air ducts between the inclined portions 10 and which are substantially triangular in cross section, are designated by the numeral 13.

Interposed between the metal sheets that are bent to form the air ducts and cooling fins just described, are vertically disposed cooling fluid ducts, each duct being formed of a pair of vertically disposed walls 14, the intermediate portions of which are spaced apart and the vertical edges of these walls are brought together and united by solder or the like and said united edges are bent into substantially zigzag shape, thus forming short inclined portions 15 with short vertical portions 16a between said inclined portions.

When the parts of the radiator are assembled, one of the water ducts is interposed between a pair of the zigzag walls forming the air ducts with the outer faces of the short vertical portions 16a that unite the inclined portions 15 of the zigzag edges of said water duct resting directly upon and permanently secured to the flat end portions of the walls 11 beyond the ends of the opening formed in providing the fins or flanges 12.

The portions 16a on the zigzag edges of the water duct may be secured to the ends of the walls 11 by solder or by the galvanizing metal into which the radiator is dipped or immersed after the parts have been properly assembled.

The water flow space between the intermediate portions of the plates 14 may be divided into two or more ducts by pressing the metal in the walls 14 inwardly on vertical lines to form ribs 16, the apices of which ribs make direct contact with each other and are united by the metal used in the galvanizing bath to which each pair of plates is subjected before they are positioned between the zigzag sheets A.

On the narrower sizes of radiators, for instance, those having a thickness of from two to two and one-half inches, I prefer to form one rib on each plate 15, thereby dividing the space

between the plates 14 into two vertically disposed water flow ducts 17.

On the intermediate sizes of radiators or those having a thickness from three to three and one-half inches two ribs are formed on each plate, thereby providing three water flow ducts as illustrated in Fig. 3 and on the larger sizes of radiators or those having a thickness from four to four and one-half inches, the plates are provided with three ribs each, thereby forming four water flow ducts.

The formation of the ribs 16 in the plates 14 materially increase the rigidity of the plates forming the water flow ducts and as said ribs are disposed at right angles to the inclined portions 10 of the members that form the air flow ducts, a very strong and rigid structure is produced that is highly effective in resisting service strains and stresses that tend to distort or bend the radiator 20 or to break the joints thereof.

After the walls A that provide the air flow ducts, and the walls 14 that form the water flow ducts are properly assembled with the portions 16a of the zigzag edges of plates 14 resting on the 25 ends of walls 11, the entire structure is dipped in galvanizing metal or the like, which is a conventional practice in the production of motor vehicle radiators and the metal in such bath rigidly unites the contacting parts of the walls 30 and seals all joints.

When the radiator is in service, the water or other cooling fluid utilized with the cooling system of an internal combustion engine flows downward through the duct 17 and air flows horizontally through the ducts 13.

Thus a relatively large volume of air flows continually over the surfaces of the walls 14 forming the water flow ducts and such action is highly effective in rapidly disseminating the heat from 40 the water or cooling fluid.

Inasmuch as the air that passes through the ducts 13 flows lengthwise over the ribs or flanges 12, the latter function to materially assist in the dissemination of heat from the cooling fluid.

The cutting of the zigzag plates A to form the heat radiating ribs or flanges provides slots or 45 openings that extend practically the entire length of the zigzag sheets, and therefore these openings expose substantial portions of the adjacent wall 50 14 of the side of the water flow ducts and as a result, the air contact with those portions of the walls 14 exposed through the slots formed by the cutting of the sheets A in the formation of the heat radiating ribs or flanges 12 is highly effective 55 in the dissemination of the heat of the water as it flows through the ducts 17.

Thus it will be seen that I have provided a motor vehicle radiator that is relatively simple in construction, inexpensive of manufacture and 60 very effective in performing the functions for which it is intended.

It will be understood that minor changes in the size, form and construction of the various parts of my improved motor vehicle radiator may be made and substituted for those herein shown and 65 described without departing from the spirit of my invention, the scope of which is set forth in the appended claims.

I claim as my invention:

1. In a motor vehicle radiator, a cellular structure comprising a series of thin metal walls bent into substantially zigzag shape to provide a plurality of inclined walls that define horizontally disposed air flow ducts, there being short flat 5 faces formed on the apices of the zigzag bent portions at the ends of said plates, a pair of spaced parallel flat plates arranged between each pair of zigzag walls, the vertical edges of which last mentioned pairs of plates are bent alternately in 10 opposite directions to form zigzag portions, the apex of each zigzag portion having a short flat surface that engages the corresponding short flat surface on the end of the adjacent zigzag wall, the contacting flat surfaces of both sets of plates 15 being permanently secured to each other, the intermediate portions of which second mentioned pair of plates are spaced apart by continuous vertically disposed ribs formed on said second mentioned plates, the apices of the ribs on each 20 pair of plates being in contact with one another throughout the height of the plates to form a plurality of separate water flow ducts, portions of the first mentioned walls between the short flat portions at the ends thereof being cut and 25 bent away from the adjacent metal to form longitudinally disposed fins that project into the air passages between said walls each fin being integrally connected to the wall from which it is cut throughout its length and the opening formed 30 by the cutting and the bending of each fin constituting a continuous slot equal to the length of the fin, and which slot exposes a substantial portion of the under-lying one of the walls that form the water flow ducts.

2. In a motor vehicle radiator, a cellular structure comprising a series of thin metal walls bent into substantially zigzag shape to provide a plurality of inclined walls that define horizontally disposed air flow ducts, there being short flat 40 faces formed on the apices of the zigzag bent portions at the ends of said plates, a pair of plates arranged between each pair of zigzag walls, the vertical edges of which last mentioned pairs of plates are bent alternately in opposite directions 45 to form zigzag portions, the apex of each zigzag portion having a short flat surface that engages the corresponding short flat surface on the end of the adjacent zigzag wall, the contacting flat surfaces of both sets of plates being permanently secured to each other, the intermediate portions of which second mentioned pairs of plates are spaced apart, vertically disposed ribs formed on 50 said second mentioned plates to divide the space between said plates into a plurality of water flow ducts, portions of the first mentioned walls between the short flat portions at the ends thereof being cut and bent away from the adjacent metal to form longitudinally disposed fins that project into the air passages between said walls, the cutting of the first-mentioned walls to form said fins being effected so that each fin is integrally connected to the wall throughout the length of the fin and the opening formed by the cutting of material to form the fin constituting a slot that 55 extends the entire length of the fin and exposes the under-lying portion of the adjacent wall of the water flow duct.

VALENTIN MILLER.
